UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 14,841, dated March 4, 1884.

Application filed January 28, 1884. Term of patent 3½ years.

To all whom it may concern:

Be it known that I, JAMES L. FOLSOM, of Brooklyn, in the State of New York, have invented a new and original Design for Carpets, 5 of which the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

15 The design consists of four flower groups, the intervening spaces being filled in with small geometric work. The group in the upper center of the photograph consists of several large leaf forms and open flowers loosely

massed, having projecting sprays of shadow leaves. The group shown in the lower center of the photograph has large central leaf forms and flower clusters and projecting lichen sprays and shadow leaves. The group shown at the left center and at the right upper and 25 lower corners of the photograph has several prominent leaf forms loosely massed with flowers, and the group shown at the right center and at the left upper and lower corners of the photograph has prominent leaf forms and projecting leaf and blossom sprays.

I claim—

The design for a carpet, substantially as shown and described.

JAS. L. FOLSOM.
